PAGE 2

Fig. 1 is a front perspective view of a combined viewer and camera attachment for a cathode ray oscilloscope or similar article, showing our new design;

Fig. 2 is a side elevational view thereof;

Fig. 3 is a top plan view thereof;

Fig. 4 is a front elevational view thereof;

Fig. 5 is an opposite side elevational view thereof; and Fig. 6 is a rear elevational view thereof.

The dominant features of the new design are shown in solid lines in the drawing. The bottom view of the combined viewer and camera attachment for a cathode ray oscilloscope or similar article is substantially plane.

We claim:

The ornamental design for a combined viewer and camera attachment for a cathode ray oscilloscope or similar article, as shown and described.
